UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

MATRIX-HOLDER FOR TYPE-CASTING MACHINES.

1,094,628.

Specification of Letters Patent. Patented Apr. 28, 1914.

Application filed February 8, 1913. Serial No. 747,203.

To all whom it may concern:

Be it known that we, JOHN SELLERS BANCROFT and MAURITZ C. INDAHL, citizens of the United States, and residents of Philadelphia, in the county of Philadelphia, State of Pennsylvania, have invented certain new and useful Improvements in Matrix-Holders for Type-Casting Machines; and we do hereby declare the following to be a full, clear, and exact description of the same, reference being had to the accompanying drawings, forming part of this specification, and to the figures and letters of reference marked thereon.

15 This invention relates to matrix holders for type casting machines of the class illustrated in Patent No. 625,998, dated May 30, 1899, when used or equipped for casting sorts as distinguished from composition.

20 With a fully equipped machine the casting of sorts can be accomplished by applying a properly perforated record strip in conjunction with a die case containing the desired character and a mold of the proper 25 point dimension, and either repeating the signal for the desired character or suspending the action of the record strip feeding mechanism. It frequently happens, however, that a matrix containing the desired 30 character is not to be found in an already assembled die case (the latter containing an extended series of characters arranged in predetermined order and relation), thereby necessitating a more or less extensive 35 arrangement of the die-case lay out to make room for the matrix containing the desired character. Moreover machines of this kind are sometimes partially equipped for use as sorts casters only in which event the record 40 strip feeding and automatic die case centering and mold adjusting mechanisms are omitted and the places of the two latter supplied by other means for retaining the die case supporting devices against lateral displacement and the mold in a fixed position 45 of adjustment set wise of the type body.

To avoid the expense and inconvenience incident to the use of the regular composition die-case for the production of sorts, it 50 is proposed to supply a special matrix holder for the purpose, one in which commercial matrices can quickly and readily be interchanged and accurately positioned relatively to the mold and centering pin of the casting

machine, and with these objects in view the 55 present invention consists in the construction, combination and arrangement of parts hereinafter fully described, the novel features whereof are specified in the appended 60 claims.

In the accompanying drawings illustrating a preferred form of embodiment of said invention, Figure 1 is a perspective view of the holder; Fig. 2 is a top plan view; Fig. 3 is a longitudinal section on the line *a—a*, 65 Fig. 2, and Fig. 4 is a transverse section on the line *b—b*, Fig. 1. Fig. 5 is a bottom plan view of a portion of the matrix section.

The same numerals designate like parts in the several views.

The improved matrix holder is composed of two relatively movable members or sections, to wit, a main or body section and a movable matrix positioning and holding section, the latter slidable in ways in the former and containing at one edge an open cell or recess provided with matrix supporting means, the open side of said cell being closed by the body section to prevent displacement of the contained matrix where the two sections are assembled for coöperation with the mold. The body section 1 consists of a flat plate provided with parallel ribs or guides 4 along opposite edges and longitudinally of its top surface for engagement with complementary ways in the die case carrier of the casting machine, and is also furnished with an open guide 5 at one end for engaging the positioning device, and with a top cover plate 6 containing a perforation or guide 7 for the passage of the centering pin by means of which the final centering and clamping of the matrix upon the mold is effected. The body section is further provided with a T-shaped slot or way 9 beneath the cover plate and extending from one end to a point opposite a gaging abutment 10, the side walls of said way being parallel and of unequal length.

The matrix section is composed of a plate 100 2 of approximately the same thickness as the body section fitted accurately to slide in the slot or way 9 and provided with a narrower extension or handle 11 at one end. The upper face of block 2 is recessed, as at 105 12, for the accommodation of a flat spring 13, one end whereof is secured to said block and the opposite or free end provided with

an inclined and shouldered off-set 14 in position to enter a perforation or recess 15 in the cover plate when the block is in engagement with gaging abutment 10.

- 5 The holder is specially designed to receive what are known commercially as cellular matrices, such as employed for composition and illustrated in Patent No. 784,245, dated March 7, 1905. Each of said matrices is in 10 form a parallelepiped containing a matrix cavity in one end, a conical centering cavity or seat in the other end, and grooved circumferentially by the intersection of two pair of side grooves of different widths. The 15 matrices are of uniform or standard dimensions and form save as to the matrix cavities which vary with the character represented. To accommodate and accurately position matrices of this variety block 2 is provided on one edge with an open sided rectangular notch or cell 15, opposed side walls whereof are furnished with inwardly projecting ribs 16 adapted to enter one pair of side grooves in the matrix. The ribs 16 are 20 preferably lightly narrower than the width of the engaged grooves so as to permit a very slight degree of longitudinal movement of the matrix when suspended thereon. When block 2 is in position within way 9 25 of the body section the adjacent wall of said way constitutes the fourth wall of the cell and effectually prevents lateral escape or displacement of the matrix deposited in said cell.
- 30 In order that the matrix cavity may be properly positioned in justified relation to the body-forming mold it is essential that the retaining notch or cell 15 in the edge of block 2 shall be accurately formed and 35 portioned to receive the matrix block and retain it in a predetermined relation to both the matrix and body sections of the holder to facilitate which, block 2 in immediate 40 proximity to the cell is preferably formed 45 in three parallel sections of which the intermediate section bears the sustaining ribs 16, while the other two contain the walls for engaging the rectangular body of the matrix to prevent axial rotation. This permits the 50 two outer sections to be assembled and milled or dressed to gage, after which the intermediate section is inserted and the whole firmly united by rivets, screws or equivalent confining means.
- 55 By prolonging one of the side walls of the slot or way 9 beyond the other, a convenient means is provided for facilitating the seating of the matrix in the cell and for directing the matrix section into said slot or way, 60 and with this in view the forward corner of block 2 on the side opposite the extended side wall is beveled as at 2^x and ends of the rib or flange of block 2, where it is intersected by the matrix receiving notch or cell 65 15 are also beveled at 3^x as shown in Fig. 5.

When it is desired to insert a matrix in the holder, the body section is supported in an inclined and inverted position, that is to say, with the cover plate under, and the handle 11 and spring 13 are grasped to flex the latter and withdraw off-set 14 from engagement with recess 15, thus releasing block 2 and permitting it to be withdrawn from its retaining slot or way 9.

The selected matrix is then inserted in cell 15 through the open side thereof, either while block 2 is detached or by first locating it in proper position upon the lower extended side wall of slot 9 while the holder is supported bottom up in an inclined vertical position and then bringing block 2 down upon it, the inclines at the entrance to the cell serving in either case to direct the matrix. With block 2 thus positioned the open side of the cell is closed so as to prevent accidental displacement of the matrix, and said block resting upon the cover plate and extended ledge is in position to be quickly shoved into the slot or way 9 until it contacts with the gaging abutment 10, thus bringing the contained matrix into registry with the centering pin opening and at the same time engaging the latch. It is not necessary, however, that the holder should be removed from the casting machine when it is desired to insert a new matrix, as this can readily be accomplished with the holder in position on the machine by simply releasing the catch and withdrawing the block and returning the latter to position after the matrix has been inserted within the cell.

Considering the degree of accuracy required in a device of this character cost of production and liability of derangement are minimized in the construction described, while the operations incident to the exchange of matrices are greatly simplified and quickly performed.

Having thus described our invention, what we claim as new and desire to secure by Letters Patent of the United States, is—

1. A matrix holder for type casting machines as described, the same including a slotted body section and a slidable matrix section fitted to the slot in the body section and provided with an open sided matrix receiving cell in one side and extending therethrough in a direction transverse to the path of movement of the slidable matrix section in the body section.

2. A matrix holder for type casting machines, composed of a body section provided with an open ended slot or way terminating in a gaging abutment, and a matrix section fitted to slide in said way and provided in one edge with a matrix retaining cell, the open side whereof is closed by one wall of said way, when the parts are assembled.

3. A matrix holder for type casting machines, consisting of a flat body section pro-

- vided with parallel ribs and an open ended way terminating at its inner end in a gaging abutment and closed on one side by a cover plate; a matrix section fitted to slide in said way and provided in one edge with an open sided matrix cell formed with supporting ribs; and a latch carried by the matrix section for locking the latter in engagement with said gaging abutment.
- 10 4. A matrix holder for type casting machines, comprising a body section provided with an open ended slot or way, the sides whereof are of unequal length; and a matrix section provided with an open sided matrix cell in one edge containing matrix engaging shoulders and fitted to slide in said open ended slot or way and to be withdrawn therefrom for the insertion or removal of a matrix.
- 15 5. A matrix holder for type casting machines, comprising two separable members, the one provided with interlocking devices for attachment to the casting machine, an open ended slot or way, a gaging member
- and a cover plate, and the other fitted to slide longitudinally within said slot or way and provided in one edge with an open sided matrix receiving cell containing sustaining ribs, and a spring latch, the latter located in a recess in the face of said last named member in position to engage a complemental locking means on the cover plate.
6. A matrix holder for type casting machines such as described, the same comprising a body section provided with an open ended slot or way, terminating at its inner end in a gaging abutment and having its side walls of unequal length; and a matrix section slidable in said way and containing a matrix sustaining cell in one edge, and a latch for engaging the body section.
